UNITED STATES PATENT OFFICE.

MAX BREMER, OF NEW BEDFORD, MASSACHUSETTS, ASSIGNOR TO THE PAIRPOINT MANUFACTURING COMPANY, OF SAME PLACE.

DESIGN FOR A COFFIN-HANDLE EAR-PLATE.

SPECIFICATION forming part of Design No. 22,548, dated June 20, 1893.

Application filed March 5, 1892. Serial No. 423,935. Term of patent 14 years.

To all whom it may concern.

Be it known that I, MAX BREMER, a citizen of the United States, residing at New Bedford, in the county of Bristol and State of Massachusetts, have invented and produced a new and original Design for a Coffin-Handle Ear-Plate, of which the following is a specification, reference being had to the accompanying drawings, forming part hereof.

10 Figure 1 is a plan, and Fig. 2 a perspective view of a coffin handle ear plate containing my design.

15 The leading feature of my design consists in an ear-plate for a coffin-handle, the outline of which plate is, when viewed in top plan, comparable to a circle having an irregular curved extension.

20 Another feature of invention consists in an ear plate of the outline referred to with a marginal upward projection which is curved on its inner side.

A is the ear-plate and a' ears. The outline of plate A is substantially the segment of a circle from a^2 to a^3 , while from a^3 to a^4 the edge of the plate is a long curve; from a^4 to a^5 the outline is a short inward curve; and from a^5 to a^6 it is a sort of fish-hook curve, the whole outline being comparable to a circle having an irregularly curved extension, as will be plain from Fig. 1. The outline described is the first and main feature of my design. Plate A having said outline, is formed with the upward projection b on its margin. This projection is curved at b' b^2 on its inner edge. 35

What I claim is—

The design for a coffin handle ear plate, as herein shown and described.

MAX BREMER.
